UNITED STATES PATENT OFFICE.

CHARLES H. LUNDY, OF WICKHAM, WEST VIRGINIA.

CONNECTER FOR ELECTRICAL CONDUCTORS.

Application filed May 22, 1924. Serial No. 715,152.

This invention relates to new and useful improvements in joints for electrical conductors, and has for its principal object to provide a means whereby the adjacent ends 5 of a pair of conductors may be joined or spliced in a comparatively simple and efficient manner.

A further object of the invention is to provide a connector of the above mentioned 10 character, wherein the same comprises a pair of cooperating members, which are adapted to be secured together for holding the ends of the conductors in locked engagement, teeth being provided on one of the members 15 for engagement with the ends of the conductors which are joined or spliced.

A further object is to provide a connector of the above mentioned character, which is simple in construction, inexpensive, strong 20 and durable, and further well adapted for the purposes for which it is designated.

Other objects and advantages of this invention will become apparent during the course of the following description.

25 In the accompanying drawing, forming a part of this specification, and in which like numerals designate like parts throughout the same:

Figure 1 is a side elevation of my improved connector showing the same in use, 30 and parts being broken away.

Figure 2 is an elevational view of the connector, with the cooperating sections secured together.

35 Figure 3 is an elevational view of one of the sections, showing the position of the adjacent ends of the conductors therein.

Figure 4 is a sectional view, taken approximately on the line 4—4 of Figure 1, and

40 Figure 5 is a similar view, taken approximately on the line 5—5 of Figure 1.

In the drawing, wherein for the purpose 45 of illustration is shown the preferred embodiment of my invention, the numeral 1 designates generally my improved connector, and the same comprises the cooperating sections, 2 and 3 respectively. The sections are preferably formed of brass or the like, although any other suitable material may be 50 substituted therefor, and I do not wish to limit myself to the particular kind of material which may be used for the purpose of carrying out the objects of the present invention.

The section 2 is open at its respective ends and is adapted to receive therein the adja-

cent ends A and B respectively, of a pair of electrical conductors, in the manner more clearly shown in Figure 3 of the drawing.

The section 2 is provided with a longitudinally extending slot or cut out portion 4, which extends for substantially the full length thereof and is further provided with the enlarged cut-out portion 5, which is arranged in the intermediate portion of the section, and cooperates with the longitudinal slot 4.

The other section 3 is of such a construction as to fit in the longitudinally extending slot 4 and is further provided with the enlarged central portion 6, for cooperation with the enlarged central cut out portion 5 of the section 2, whereby a substantially tubular joint or splice is provided, for securing the adjacent ends of a pair of electric conductors. It is, of course, to be understood, that the inner face of the section 3 is curved to conform to the shape of the ends of the wire conductors, which are supported in the ends of the section 2, and the section 3 is further provided with the teeth 7, on the bottom edges of the end portions thereof, for engagement with the adjacent portions of the adjacent ends A and B of the electrical conductor wires, in the manner as clearly illustrated in Figures 1 and 4 of the drawings.

For the purpose of securing the co-operating interfitting sections together, whereby the ends of the electrical conductor wires may be securely held fastened together, I provide the clamping screw 8. The clamping screw passes through a suitable opening 9, provided in the intermediate portion of the section 2, and extends between the ends 90 of the electrical conductor wire, and is threaded into a threaded opening 10 provided in the section 3. This construction is more clearly illustrated in Figure 5 of the drawing. The opening 9 provided in the section 2 may be countersunk for receiving the head 11 of the screw 8.

It will thus be seen from the foregoing description, that a connector for electrical conductors has been provided, which is of such a construction as to enable the same to be readily and easily placed in an operative or inoperative position, and will securely hold the adjacent ends of a pair of electrical conductor wires joined or spliced against accidental disengagement therefrom. The provision of the teeth on one of the cooper-

ating sections will prevent the longitudinal movement of the conductors, when the ends thereof are within the connector. A connector of the above mentioned character may 5 be manufactured at a very low cost and will further be strong and durable.

While I have shown the preferred embodiment of my invention, it is to be understood that various changes in the size, shape, 10 and arrangement of parts may be resorted to, without departing from the spirit of the invention and the scope of the appended claim.

Having thus described my invention, what 15 I claim is:

A connector for holding two electrical conductors in end to end relation, comprising a pair of cooperating interfitting sec-

tions, one of said sections being semi-cylindrical in formation so as to provide a longitudinally extending slot, the edges of which are provided with notches, the other section being arcuate in cross section and formed to fit in said slot and to form a substantial cylinder therewith, and having side extensions adapted to be received in said notches, a pair of series of teeth formed on the inner face of the last mentioned section, the teeth of the pair of series being pitched inwardly, inner teeth of the pair being spaced from 20 each other, and a screw piercing the intermediate portion of the first section and threadedly engaged with the intermediate portion of the second section.

In testimony whereof I affix my signature.

CHARLES H. LUNDY.
